UNITED STATES PATENT OFFICE

2,271,392

AUTOMATIC BURGLAR ALARM

Albert G. Eckhardt, St. Louis, Mo.

Application June 7, 1940, Serial No. 339,237

2 Claims. (Cl. 116—89)

This invention relates to new and useful improvements in automatic burglar alarms.

Among the main objects of the invention is the provision of an alarm which is adapted to be secured to a door frame or a window sash and has a movable plunger releasable by the opening movement of the door or the other sash to fire a blank cartridge located in a suitable holder, said holder being displaceable to move the cartridge out of the path of said plunger when the alarm is not used.

Another object of the invention is to provide an automatic burglar alarm having a support, a releasable spring-actuated plunger mounted in said support, and a cartridge holder pivotally mounted at its outer end in said support and having its inner end adapted to receive a cartridge and hold it in the path of said plunger, said holder being manually movable on its pivotal mounting to bring the cartridge end out of the path of said plunger when it is not desired to use the alarm.

Additional objects of the invention are to provide an automatic burglar alarm which is of simple construction, is efficient in operation, and which can be rendered inoperative by displacing the cartridge holder thereof.

With these and other objects in view, my invention consists in certain novel features of construction and arrangement of parts hereinafter more fully described and claimed, and illustrated in the accompanying drawing, in which—

Figure 1 is a front elevational view of my burglar alarm as applied to a door.

Figure 2 is a top plan view thereof.

Figure 3 is a vertical cross section taken on line 3—3 of Figure 1.

Figure 4 is a similar view but showing the plunger released and the cartridge held in a displaced position.

Figure 5 is an enlarged cross section taken on line 5—5 of Figure 3.

Figure 6 is an enlarged cross section taken on line 6—6 of Figure 4.

Referring by numerals to the accompanying drawing, 10 indicates a support which is channel-shaped in cross section having longitudinal flanges 11 united by a web portion 12. This support is preferably stamped from sheet steel and the upper end 14 of the web portion 12 is bent at right angle over the corresponding ends 11a of flanges 11 and is formed with an outwardly opening notch 15. A pair of spaced-apart ears or lugs 16 is stamped out of the web portion 12 and bent outwardly in a plane parallel with said end

14. Each lug 16 is formed with an aperture 17 and these apertures are in axial alignment with the inner end of notch 15.

The other ends of flanges 11 are each formed with a lug or ear 18 projecting forwardly in the same plane with said flanges. Lugs 18 are formed with aligned apertures in which are secured the ends of a horizontally disposed pin 19.

Pivotaly mounted on said pin 19 adjacent to said ear 18 are the ends 20 of the parallel legs 21 of a cartridge holder 22. This holder is U-shaped and the bite portion 24 connecting the legs 21 is formed with an aperture 25 which is in axial alignment with the apertures 17 of lugs 16. This aperture 25 is of a suitable diameter to receive a cartridge A. A coiled spring 26 is arranged on pin 19 and yieldably maintains said holder in its home or firing position. In this position the holder is folded inwardly between the flanges 11 with the bite portion 24 and the cartridge A presented against and in alignment with the apertures 17.

Slidably mounted in apertures 17 longitudinally of support 10 is a plunger 27, the inner end 28 of which is pointed and presented against holder 22 and cartridge A. The outer end of this plunger is bent at right angle and extends laterally of said support 10, as indicated at 29. When this plunger is cocked or retracted the arm

29 is disposed past the end 14 and overlies and bears against one of the legs formed by the notch 15. The pointed end 28 is spaced a suitable distance from cartridge A. The arm 29 lies in the path of movement of the movable closure member,

such as a door, and when the latter is moved into open position said arm 29 is moved in an arc to clear the leg of said notch 15 whereupon said plunger 27 is released and moves inwardly with the end 28 striking and firing the cartridge A.

The actuating force of the plunger 27 is supplied by a coiled compression spring 30 which is positioned on said plunger intermediate the outer lug 16 and a collar 31 fixed on said plunger. This spring urges the plunger in the direction against the holder and the cartridge and when the plunger is retracted or moved into firing position the force of said spring is increased so that when said plunger is released sufficient force is pro-

duced to fire the cartridge.

When the holder 22 is displaced from its firing position the collar 31 comes to rest against the inner lug 16 and limits the inward movement of said plunger. This holder is displaceable or movable out of its firing position to prevent acci-

dental discharge of the cartridge when it is not desired to use the alarm.

To move the holder 22 out of its operative or firing position the bite portion 24 is provided with an outward extension 24a to provide a better hold. The holder is moved away from plunger 27 on the pivot point 19, as shown in Figure 4.

The support 10 is attached in position by means of screws 32 engaging the web portion 12 through apertures 33 formed therein. It can be attached to the vertical member B of a door frame so that the arm 29, when the plunger 27 is cocked, lies in the path of the door C. In the case of a window, the support 10 is attached on the inside to the bottom rail of the upper sash and the arm 29, after the plunger 27 is cocked, is brought above the top rail of the bottom sash. Thus when the latter is moved upwardly it engages said arm and releases the plunger.

The end of arm 29 is provided with an aperture 29a for receiving one end of a cord or thin wire, the other end being connected to a closure member. Thus the device 10 can be located remotely from the closure member. When said member is opened, the cord pulls on said arm to disengage it from the notched end 14 and release the pin 27.

The coiled spring 26 serves to bring the cartridge holder 22 to its home or firing position.

In order to prevent said holder when moved in inoperative position from returning to its home position, suitable means are provided for yieldably locking said holder in its inactive position. This means preferably is in the form of protuberances 34 formed on the inside of the lower ends 18 and adapted to engage seats 35 formed on outside faces of side members 21. These protuberances 34 and seats 35 are so arranged that they are in register with each other only when the holder 22 is in a moved position, as shown in Figure 4; at other times they are disengaged and the holder free to return to its firing position.

In this manner the holder is safely held in inoperative position and the accidental discharge of the cartridge is prevented.

By mounting the holder 22 movably in member 10, said holder can be easily displaced from its firing position and the pin 27 released without danger of discharging the cartridge. Furthermore, the cartridge can be more easily replaced.

Arm 29 can be turned to the left or to the right of member 10 to fit the closure member.

While I have shown and described herein the preferred form of my invention, it is to be understood that various changes in the construction and arrangement of parts of my burglar alarm can be made without departing from the spirit of my invention.

I claim:

1. In an automatic burglar alarm, the combination of a stationary support channel-shaped in cross section, a pair of spaced-apart lugs extending transversely from the web portion of said support, a pin slidably mounted in said lugs and having its upper end bent at right angle to its axis, a spring for forcing said pin inwardly into firing position, means on the upper end of said support for engaging said bent end and holding said pin in a retracted position, said bent end being operable by the opening of a closure member to release said pin, a cartridge holder of inverted U-shape having its ends pivotally mounted to the side flanges of said support and adapted to hold a cartridge in a firing position for said pin, said holder being manually movable from its vertical position to a horizontally outward position to displace said cartridge from firing position, a spring for yieldably maintaining said holder in firing position, and cooperating means on said flanges and the ends of said holder for frictionally retaining said holder in a cartridge displaced position against the action of said last mentioned spring.

2. In a device of the class described, the combination with a stationary support channel-shaped in cross section and a firing pin slidably mounted therein, of a cartridge holder of inverted U-shape and having its ends pivotally mounted in the flanges of said channel support said support adapted to hold a cartridge in a firing position for said pin, said holder being manually movable into a displaced position to place said cartridge out of striking range of said pin, means for holding said holder in cartridge firing position, and cooperating protuberances and seats on the flanged ends of said support and the ends of said holder for locking said holder in said displaced position against the action of said holding means.

ALBERT G. ECKHARDT.
